UNITED STATES PATENT OFFICE

98,060

DESIGN FOR AN AUTOMOBILE BODY OR SIMILAR ARTICLE

Robert M. Ferguson, Jr., Newark, N. J.

Application April 23, 1935, Serial No. 56,521

Term of patent 7 years

To all whom it may concern:

Be it known that I, Robert M. Ferguson, Jr., a citizen of the United States, residing in Newark, county of Essex, State of New Jersey, have invented a new, original, and ornamental Design for an Automobile Body or Similar Article, of which the following is a specification, reference being had to the accompanying drawing, forming part thereof.

Figure 1 is a side elevation of an automobile body showing my new design.

Figure 2 is a front elevation.

Figure 3 is a rear elevation.

The design consists of a long, low-hung, car body, tapering slightly from the front downwardly to the rear, with an arched or curved roof, the front portion of which tapers down-

wardly to a substantially V-shaped head bulging over the V-shaped slanted windshield. The sides at the front of the body as well as the sides of the engine hood are curved inwardly and taper gradually into a V-shaped radiator front, from which the front fenders taper rearwardly along the curved sides to the substantially straight portion of the body.

In the rear, the body skirts are convex, curving inward below the rub-bar, terminating in a substantially flat panel, the rear wheel portion being enclosed.

I claim:

The ornamental design for an automobile body or similar article as shown and described.

ROBERT M. FERGUSON, JR.
